UNITED STATES PATENT OFFICE

ARTHUR CLARE STRAYER, OF NEW BRIGHTON, PENNSYLVANIA

LOCK-SEAL BAG

Application filed August 19, 1929. Serial No. 386,943.

This invention relates to a bag especially adapted to be used for the purpose of depositing money after banking hours and has for one of its objects to provide a bag of this character which shall be equipped with a closure adapted to seal the bag in a manner to positively prevent the loss or extraction therefrom of any coins, and which shall be equipped with means adapted to secure the closure in bag sealing position against opening by anyone except the depositor.

The invention has for a further object to provide a bag of the character stated wherein the closure and the closure securing means shall be of such construction as to permit the bag to pass freely through the chute and into the safe with which banks are now equipped for the reception of deposits after banking hours.

20 The invention has for a further object to provide a bag of the character stated wherein the closure shall be of such construction as to permit it to be easily and quickly moved into bag sealing or unsealing position, and 25 wherein the securing means shall be adapted to be easily and quickly adjusted to secure the closure in bag sealing position or to release the closure for movement into bag unsealing position.

30 The invention has for a still further object to provide a bag of the character stated which shall be strong and durable and capable of being manufactured and sold at a comparatively low cost.

35 With the foregoing and other objects in view, the nature of which will appear as the description proceeds, the invention consists in the construction, combination and arrangement of parts hereinafter fully described and claimed, and illustrated in the accompanying drawing, wherein:

40 Figure 1 is a view in front elevation of the upper portion of a bag constructed in accordance with my invention, the closure being shown secured in bag sealing position;

45 Figure 2 is a view similar to Figure 1 with the closure opened or in bag unsealing position;

50 Figure 3 is a view partly in top plan and

partly in horizontal section of the bag with the closure in opened position;

Figure 4 is a sectional view on an enlarged scale taken on the vertical plane indicated by the line 4—4 of Figure 2;

55 Figure 5 is a sectional view on an enlarged scale taken on the horizontal plane indicated by the line 5—5 of Figure 1;

Figure 6 is a sectional view on an enlarged scale taken on the vertical plane indicated by the line 6—6 of Figure 1, and

Figure 7 is a sectional view taken on the horizontal plane indicated by the line 7—7 of Figure 1.

60 Referring in detail to the drawing, 1 designates the bag and 2 the closure therefor. The bag 1 comprises a body portion 3, which may be made from duck or the like and a mouth portion 4, which may be made from leather or the like.

65 The body portion 3 and the mouth portion 4 comprise front sides, rear sides and folded lateral sides or edges, which may be stitched together, as indicated at 5, or securely connected in any other suitable manner. The 70 sides of the body portion 3 are designated 3^a, 3^b and 3^c, respectively, and the sides of the mouth portion 4 are designated, 4^a, 4^b and 4^c, respectively. The closure 2 comprises a front flap 6, a rear flap 7, and tabs 8 and 9 extending

75 from the ends of the flaps and preferably formed integrally with the flap 7. The lower portions of the flaps 6 and 7 are arranged within the upper end of the mouth portion 4 and are secured to the sides 4^a and 4^b of said portion by stitching 10 or in any other substantial manner. The ends of the flaps 6 and 7 are connected together by stitching 11 or

80 in any other suitable manner. 85 The flaps 6 and 7 and tabs 8 and 9 are each folded upon itself, and the folds or plies thereof are stitched together, as at 12, to provide pockets 13 in which flat strengthening bars 14 are arranged. The flaps 6 and 7 are provided with registering eyelets 15 and 16, respectively, which are arranged at the transverse center and between the reinforcing bars 14 thereof. The sides 4^a and 4^b of the mouth 90 portion 4 are provided with registering eyelets 17 and 18, respectively, which are arranged at the

95

100

transverse center thereof and with which the eyelets 15 and 16 register when the flaps 6 and 7 are folded upon the side 4^a to effect the closing or sealing of the bag. The tabs 8 and 9 are provided at their outer ends and outwardly beyond their reinforcing bars 14 with eyelets 19 and 20, respectively, which register with each other and with the eyelets 15 to 18 when the tabs are folded against the side 4^b 5 of the mouth 4 after the folding of the flaps 6 and 7 against the side 4^a.

The flaps 6 and 7 are folded along the stitch lines 10 and the tabs 8 and 9 are folded along the stitch lines 11. When the flaps 6 15 and 7 and tabs 8 and 9 are folded in the manner set forth, the closure 2 is in bag sealing position, and it is secured in this position by means which comprise a headed bolt 21 and a lock 22. The bolt 21 passes through the 20 eyelets 15 to 20 with its head 21^a in contact with the outer side of the eyelet 21 and with its apertured end 21^b extending beyond the eyelet 16. The lock 22 is engaged with the bolt 21 by having its shackle 22^a passed 25 through the opening 21^b of the bolt.

When the closure 2 is in opened position, the flaps 6 and 7 thereof extend upwardly from the sides 4^a and 4^b of the mouth 4. As the flaps 6 and 7 are flexible and connected together at their ends, as the inner ends of the reinforcing bars of each flap are relatively spaced, and as the outer ends of the reinforcing bars of each flap terminate with the corresponding ends of the flap, the flaps will, 30 when engaged at their transverse centers and said centers moved away from each other, assume angular relation and thus provide an opening of substantial rectangular formation and through which the money may be readily placed within or removed from the bag. The reinforcing bars 14 of the flaps 6 and 7 are maintained in relatively spaced relation by the lines of stitching 11 and the eyelets 15 and 16, and the two reinforcing bars of each 35 flap causes those portions of the flap that are located at opposite sides of the eyelet of the flap to assume an angular position when the flaps are separated whereby to provide a rectangular opening for the bag.

50 After the money has been placed in the bag, the flaps 6 and 7 are moved into contact with each other, and the contacting flaps are then folded upon the front side 4^a of the mouth 4, and thereafter the tabs 8 and 9 are folded 55 against the rear side 4^b of the mouth with their free ends in overlapped relation.

The bolt 21 is then passed through the registering eyelets 15 to 20. The shackle of the lock 22 is then passed through the 60 opening 21^b of the bolt 21, and thereafter the shackle is swung into closed position.

When the closure 2 is in bag sealing position, the upper edge and the upper corners of the mouth 4 are so effectively sealed as to 65 positively prevent the loss or extraction of

any coins from the bag without first opening the lock 22 and withdrawing the bolt from the closure. In view thereof, and as only the depositor may open the lock 22, the possibility of the surreptitious removal of the 70 whole or any part of the contents of the bag is reduced to the minimum. Due to the construction of the closure and the securing means therefor, the bag will pass freely through the chute and into the safe of the bank, it being understood that a chute of this type is accessible for the deposit of money after banking hours and from a point outside of the bank, and that on the opening 75 of the bank, the depositor is handed the bag which is opened in the presence of the receiving teller.

Small size bags have each of the flaps 6 and 7 provided with two of the reinforcing bars 14 and have each tab 8 and 9 thereof provided with one of the reinforcing bars. Bags of larger size have each of the flaps 6 and 7 thereof provided with three or more of the reinforcing bars 14 and have each of the tabs 8 and 9 thereof provided with two 80 or more of the reinforcing bars, the number of the reinforcing bars 14 used in each of the flaps 6 and 7 and in each of the tabs 8 and 9 depending solely upon the size of the bag.

As the reinforcing bars 14 are relatively 85 spaced and as the spaces between the reinforcing bars are in registration when the closure is in bag sealing position, the closed mouth of the bag may be folded along lines intersecting the registering spaces between the reinforcing bars and particularly along the line intersecting those registering spaces that are located at the transverse center of the mouth, and due thereto the closed mouth is of such flexibility that it will not tend to bind in the deposit chute leading to the safe. The eyelet 20 comprises an outer member 20^a, and an inner member 20^b which pass through the tab 9 in telescopic relation and have their remote ends flanged outwardly 90 into contact with the opposite sides of the tab. This eyelet also comprises a sleeve 20^c which is arranged within the members 20^a and 20^b and has its ends flanged outwardly 95 into contact with the flanged ends of said members. The bolt 21 passes through the eyelet member 20^c, and this member has such frictional contact with the bolt as to secure it to the tab 9 against accidental displacement therefrom.

100 While I have described the principle of the invention, together with the structure which I now consider the preferred embodiment thereof, it is to be understood that the structure shown is merely illustrative and that such changes may be made, when desired, as fall within the scope of the invention as claimed.

105 I claim:

110 1. A bag having the front and rear sides 115

thereof provided with registering openings, a closure flap attached to said front side and folded downwardly against said side, a second closure flap attached to said rear side and attached at its ends to the ends of said first closure flap and folded downwardly over said first closure flap, said closure flaps being provided with openings registering with said first openings, tabs extending from the ends of said second closure flap and folded against said rear side with their free ends arranged in overlapped relation and provided with openings registering with said other openings, and locking means including a retaining member passing through the openings.

2. A bag having the front and rear sides thereof provided with registering openings, a closure flap attached to said front side and folded downwardly against said side, a second closure flap attached to said rear side and attached at its ends to the ends of said first closure flap and folded downwardly over said first closure flap, said closure flaps being provided with openings registering with said first openings, tabs extending from the ends of said second closure flap and folded against said rear side with their free ends arranged in overlapped relation and provided with openings registering with said other openings, reinforcing bars carried by each closure flap at opposite sides of the opening thereof, a reinforcing bar carried by each tab between the opening therein and said second closure flap, and locking means embodying a retaining member passing through the openings.

In testimony whereof I hereunto affix my signature.

ARTHUR CLARE STRAYER.
